UNITED STATES PATENT OFFICE.

CHARLES A. LAFFITEAU AND WILLIAM C. HENDRIX, OF SAVANNAH, GEORGIA.

SPARK PLUG FOR INTERNAL-COMBUSTION MOTORS.

Application filed May 7, 1924. Serial No. 711,715.

To all whom it may concern:

Be it known that we, CHARLES A. LAFFITEAU and WILLIAM C. HENDRIX, citizens of the United States, residing at Savannah, in the county of Chatham and State of Georgia, have invented certain new and useful Improvements in Spark Plugs for Internal-Combustion Motors, of which the following is a specification.

10 This invention relates to a spark plug for internal combustion motors, and has for its object to provide a plug of such class, in a manner as hereinafter set forth, with a plurality of primary electrodes and a secondary 15 electrode common to said primary electrodes to form a plurality of independent ignition points or gaps and whereby each of said primary electrodes can independently coact with the secondary electrode in a manner so 20 that if a primary electrode when coacting with the secondary electrode becomes inactive, from some cause, one of the other primary electrodes can be substituted therefor to coact with the secondary electrode without 25 disconnecting the plug from the motor.

A further object of the invention is to provide, in a manner as hereinafter set forth, a spark plug with means to permit of substituting an unimpaired electrode carrying 30 core of insulation for a damaged core when occasion requires without stopping the operation of the motor.

A further object of the invention is to provide, in a manner as hereinafter set forth a 35 spark plug, having means to form a series of independent spark gaps and further with means whereby the gaps can be independently employed for sparking purposes or employed simultaneously.

40 Further objects of the invention are to provide, in a manner as hereinafter set forth, a spark plug, which is simple in its construction and arrangement, strong, durable, compact, adjustable, thoroughly efficient in 45 its use, readily assembled, and comparatively inexpensive to manufacture.

With the foregoing and other objects in view, the invention consists of the novel construction, combination and arrangement of 50 parts, as hereinafter more specifically described and illustrated in the accompanying drawings, wherein is shown an embodiment of the invention, but it is to be understood that changes, variations and modifications 55 can be resorted to which come within the scope of the claims hereunto appended.

In the drawings wherein like reference characters denote corresponding parts throughout the several views:—

Figure 1 is a side elevation of a spark 60 plug in accordance with this invention.

Figure 2 is a vertical sectional view thereof and further showing the adaptation of the plug in connection with an internal combustion motor.

Figure 3 is a section on line 3—3, Figure 2.

Figure 4 is a section on line 4—4, Figure 2.

Figure 5 is an elevation of the core of insulation.

Figure 6 is an inner end view of the core.

Figure 7 is an inner end view of the plug.

Figure 8 is a fragmentary view, in vertical section, showing the position of the shell when substituting a new core without 75 discontinuing the operation of the motor.

Referring to the drawings in detail, 1 denotes conventionally a portion of the wall of a cylinder of an internal combustion engine and to which is adapted to be detachably connected the spark plug. The wall 1 has an opening 2 with the wall thereof threaded.

A spark plug in accordance with this invention comprises a metallic shell formed of an outer portion 3 and an inner portion 4 and with the former of greater diameter than the latter. The inner portion 4 is inset with respect to the outer portion 3, whereby shoulders 5 and 6 are formed. The 90 inner portion 4 is peripherally threaded, as at 7, and interiorly threaded at its inner end, as at 8. The length of the inner portion 4 is such that when the shell is mounted in position, the said inner portion 4 will 95 extend a substantial distance within the cylinder of the engine. When the shell is connected to the cylinder, the inner portion 4, extends through the opening 2 and the threads of said portion 4 engage with the 100 threads on the wall of the opening 2 and further when the shell is mounted in position the shoulder 6 abuts against the outer face of the wall 1.

The inner end of the portion 4 of the shell 105 is closed by a peripherally threaded disk 9 which engages with the internal threads 8 of the portion 4. The disk 9 is grooved, as at 10, to facilitate the positioning thereof, and said disk 9 is of substantial thickness 110 but of such thickness as not to close entirely that part of the inner portion 4 which pro-

jects inwardly from the inner face of the wall 1.

The inner end of the portion 4 of the shell is provided with a pair of diametrically opposed openings 11 of substantial diameter and said openings 11 are arranged in the portion 4 of the shell, outwardly with respect to the disk 9 when the latter is secured in the inner end of the shell. Preferably the length of the inner portion 4 of the shell is such that when the shell is mounted in position, it will extend a sufficient distance into the motor cylinder so that the openings 11 will be arranged between the disk 9 and the inner face of the wall 1, or in other words the diameter of each of the openings 11 is such whereby the openings will be positioned to extend from the disk 9 to the inner face of the wall 1, as clearly shown in Figure 2. The openings 11 allow for the entrance of the compressed charge into the shell outwardly with respect to the disk 9 to provide for the ignition of the charge. The purpose of the disk 9 will be hereinafter referred to.

The inner face of the outer portion 3 of the shell, at its outer end, is threaded, as at 12, for a purpose to be presently referred to. Seated against the shoulder 5 is a metallic washer 13, having its top edge formed with a lug 14. The shoulder 5 is bevelled as well as the lower or inner edge of the washer 13. The threads on the inner face of the outer portion 3 of the shell are engaged by a peripherally threaded flanged packing gland 15 which abuts against a packing element 16 arranged within the outer portion 3 of the shell.

Arranged within the shell and extending through and projecting outwardly with respect to the gland 15 is a core of insulation and which is formed of an outer cylindrical portion 17, an inner cylindrical portion 18 of the same diameter as the portion 17, and an intermediate portion 19 of greater diameter than either of the portions 17, 18. The outer edge of the intermediate portion 19 is bevelled, as at 20, and the inner edge 21 of said portion 19 is plane and provided with a recess 22 and into which extends the lug 14 of the washer 13. When the core is mounted in position, it is surrounded by the washer 13 and the latter abuts against the edge 21 of the intermediate portion 19 and with the lug of the washer 13 extending into the recess 22. See Figure 5. The setting up of the washer 13 with respect to the intermediate portion 19, in the manner as stated, prevents the washer 13 from shifting circumferentially with respect to the inner portion 18 of the core.

The inner terminus of the inner portion 18 of the core, is convex in cross section, as indicated at 23, and said inner terminus is provided with a series of pockets which

merge into each other at the inner ends thereof, and the number of the pockets depends on the number of primary electrodes employed, and as the plug is shown as provided with four primary electrodes, four pockets are formed in the inner terminus of the inner portion 18, and said pockets are radially disposed. The pockets, at the inner terminus of the inner portion 18 of the core, are indicated at 24, 25, 26 and 27, and the top wall of each of said pockets conforms in curvature to the convex curvature of the inner terminus of the inner portion 18. The pockets merge into each other at the axis of the core at the inner terminus of the inner portion 18. When the number of primary electrodes is increased, the number of pockets will be correspondingly increased, and the same arrangement is had when the number of primary electrodes is decreased. The length of each of the pockets is materially greater than the width thereof and the outer end wall of each of said pockets is semi-circular, as at 28.

The outer portion 17 of the core at a point a substantial distance from the outer end thereof, has its periphery provided with a series of spaced concavities and the number of said concavities will correspond to the number of primary electrodes, and as shown the said outer portion 17 of the core is formed with four concavities indicated at 29, 30, 31 and 32.

The intermediate portion 19 of the core is mounted in the outer portion 3 of the shell, and is seated against the washer 13 and has bearing thereagainst the packing element 16. See Figure 2. The gland 15 when secured to the outer portion 3 of the shell, clamps the core in position. The diameter of the portions 17 and 18 of the core is such as to provide for said portions to snugly engage respectively the gland 15 and the inner portion 4 of the shell. The diameter of the intermediate portion 19 of the core is such as to snugly engage the inner face of the outer portion 3 of the shell.

Embedded within the core is a plurality of primary electrodes, as shown four in number, and which are indicated by the reference characters 33, 34, 35 and 36. The primary electrodes are positioned between the axis and the periphery of the core and are arranged equi-distant with respect to each other. Each of the primary electrodes has an angle-shaped upper terminal 37 which projects outwardly and an angle-shaped inner terminal 38, which projects inwardly. Each of the primary electrodes extends from a concavity to a pocket or in other words, the electrode 33 extends from the concavity 29 to the pocket 24, the electrode 34 from the concavity 30 to the pocket 25, the electrode 35 from the concavity 31 to

the pocket 26 and the electrode 36 from the concavity 32 to the pocket 27. Each of the electrodes has its inner terminal portion 38 snugly engaging the upper wall of its respective pocket, and each of said electrodes when entering its respective pocket is spaced from the end wall 28 of the pocket. The free ends of the inner terminal portions of the electrodes are positioned a substantial distance from the inner ends of the pockets. See Figure 6.

The upper terminal portions 37 of the electrodes extend into the concavities a sufficient distance. See Figure 3.

15 Embedded within the core is an angle-shaped secondary electrode, which is common to said primary electrodes and said secondary electrode comprises a leg 39 positioned axially of the core and a leg 40 disposed at right angles with respect to the axis of the core. The leg 39 is of a length slightly less than the length of the inner portion 18 of the core, and the lower end of said leg 39 projects into the pockets at the points of emergence thereof, and the said inner end of the leg 39, which is indicated at 41, associates with the inner terminal portions 38 of the primary electrodes. The end 41 is positioned a substantial distance from each of said inner terminals 38 and provides in connection therewith a spark gap. The leg 40 projects outwardly from the inner portion 18 of the core and extends into the washer 13, as indicated at 42. See Figure 4. The leg 40 has electrical contact with the washer 13 and said leg 40 is arranged between a pair of primary electrodes. See Figure 4.

Shiftably mounted upon the outer end of the portion 17 of the core is a cap member 43 of insulation and which is provided with a socket 44 for the reception of the upper portion of the core and which extends into the socket 44 a sufficient distance so that the cap member will inclose the concavities formed in the core. See Figure 2. The cap member 43 is what may be termed a circuit opening and closing element and is provided with a plurality of binding posts, and the number of said posts corresponds to the number of primary electrodes and as shown the cap member 43 has connected therewith four binding posts, indicated at 45, 46, 47 and 48, and when the primary electrodes are to be independently used, but one circuit wire is employed, as indicated at 49, and which by way of example is attached to the binding post 47, but if the primary electrodes are to be simultaneously employed, then to each of the binding posts a circuit wire would be attached.

Carried by each of the binding posts, as well as depending therefrom, is a resilient conductor 50, having its lower end offset, as at 51, and fixed to said offset lower end is a contact 52 which is slidably mounted in the

cap member 43 and extends into a concavity for engagement with the angle-shaped upper terminus 37 of a primary electrode for the purpose of electrically connecting said electrode with the circuit conductor 49. 70

The resilient conductors 50, in connection with the contacts 52, act as means for connecting the cap member 43 with the core, due to the fact that the resilient conductors 50 normally maintain the contacts 52 in the concavities, but the engagement is such as not to prevent shifting of the cap member 43 upon the core, when occasion requires. 75

The construction and arrangement of the plug is such, that the primary electrodes can be thrown independently in active position. As shown in Figure 2, the primary electrode 35 is in active position due to the fact that it is electrically connected with the circuit connection 49. Now, if the primary electrode 35 should become impaired or damaged, the cap member 43 can be shifted, so that the circuit wire 49 can be electrically connected to any one of the primary electrodes, by way of example, the primary electrode 36, and this connection is had as the cap member 43 will be shifted so that the resilient conductor 50, carried by the binding post 47 will be moved to a position whereby the contact 52 carried thereby will engage in the concavity 42 and electrically connect with the upper terminal portion 37 of the primary electrode 36. The foregoing operation is carried out until all of the primary electrodes have become active and if all of said primary electrodes become impaired or damaged, then the core is removed and a new one with the primary and secondary electrodes substituted and connected to the shell. 95

When it is desired to substitute a new core, the shell is shifted outwardly with respect to the wall 1, until the openings 11 are closed by the wall of the opening 2, and owing to the fact that the inner end of the portion 4 of the shell is closed by the disk 9, the cylinder will be blocked off without discontinuing the operation of the motor. 100

The damaged core is then removed and a new one substituted and after the latter has been secured in position the shell is then shifted to the position shown in Figure 2. If the inner end of the shell was not provided with the disk 9, the substitution of a new core could not be had without discontinuing the operation of the motor. 115

The providing the inner terminus of the core of convex curvature, as well as the top walls of the pockets, overcomes short circuiting, due to clogging up of the spark gaps or the fouling of the inner ends of the electrodes by an accumulation of oil. The curvature at the inner end of the core causes the oil or constituents of the charge to flow away from the inner termini of the elec- 125

trodes, then any accumulation upon the plug 9 would be vaporized.

The plug construction is such that it provides for a plurality of independent spark-
5 ing points so that if one point becomes dead, another point can be switched in and under such conditions it provides for a single plug having means whereby it will equal the employment of a plurality of plugs each
10 formed with a single spark gap or firing point, as a plug in accordance with this invention, having by way of example four firing points or spark gaps, will take the place of four plugs each provided with a
15 single firing point or spark gap, therefore reducing materially the cost of maintenance.

It is thought that the many advantages of a spark plug, in accordance with this in-
20 vention, can be readily understood, and although the preferred embodiment of the in-
vention is as illustrated and described, yet changes in the details of construction can be had which will fall within the limits of
25 the invention as claimed.

What we claim is:—

1. A spark plug comprising a shell, a core
mounted therein and provided at its inner
end with a plurality of pockets, a secondary
30 electrode carried by the core and having
its inner end arranged axially with respect
to said pockets and its upper end projecting
laterally from the core, a plurality of pri-
mary electrodes mounted in the core and
35 having their inner ends extended in said
pockets and spaced from the inner end of
said secondary electrode, said secondary

electrode common to said primary elec-
trodes, and shiftable means carried by the
core and adapted to selectively engage with
40 said primary electrodes to cause the select-
ed primary electrode to coact with the sec-
ondary electrode for ignition.

2. A spark plug comprising a core adapt-
ed to be connected to the cylinder and pro-
vided with a plurality of primary electrodes
having exposed inner ends and further pro-
vided with a secondary electrode having an
exposed inner end common to the exposed
inner ends of the primary electrodes, said
secondary electrode having its outer end
projecting from said core, said primary
electrodes having their outer ends ar-
ranged within said core and exposed, and
55 a shiftable cap member mounted on said
core and provided with spring controlled
circuit opening and closing means selective-
ly engaging with the exposed ends of said
primary electrodes to cause the selected
50 primary electrode to independently coact
with the secondary electrode for ignition.

3. A spark plug comprising an electrode
carrying core having its inner end of con-
60 vex curvature and provided with a plural-
ity of pockets having the top walls thereof
corresponding in curvature to the curvature
of said inner end, the curvature of said in-
ner end and walls of the pockets overcoming
65 short circuiting.

In testimony whereof, we affix our sig-
70 natures hereto.

CHARLES A. LAFFITEAU.
WILLIAM C. HENDRIX.
